UNITED STATES PATENT OFFICE.

SAMUEL G. MUSSER, OF LOS ANGELES, CALIFORNIA.

METHOD OF OBTAINING METAL FROM ORE.

1,365,844.

Specification of Letters Patent.

Patented Jan. 18, 1921.

Original application filed July 19, 1917, Serial No. 181,474. Divided and this application filed January 19, 1918, Serial No. 212,613. Renewed May 13, 1920. Serial No. 381,195.

To all whom it may concern:

Be it known that I, SAMUEL G. MUSSER, a citizen of the United States, residing at Los Angeles, in the county of Los Angeles and State of California, have invented a new and useful Method of Obtaining Metal from Ore, of which the following is a specification.

This invention relates to the utilization of centrifugal action to force metalliferous ores into contact with a body of mercury, and an object of the invention is to effect maximum amalgamation of the metal passing through the device.

Another object is to minimize the loss of mercury used in the amalgamating operation.

Another object is to minimize internal pressures so as to reduce the liability to leakage of the mercury through the various joints between the different parts of the apparatus employed.

Other objects and advantages will appear in the subjoined detail description.

This is a division of my copending application for patent for centrifugal amalgamator, filed July 19, 1917, Sr. No. 181,474.

The accompanying drawings illustrate a type of machine whereby the new method is effected.

Figure 1 is an elevation from the discharge side partly in vertical mid section of the amalgamator.

Fig. 2 is a plan section on line indicated by x^2-x^2 , Fig. 1.

Fig. 3 is a plan section on the irregular line indicated by x^3-x^3 , Fig. 1.

Fig. 4 is a sectional detail of a portion of the shell showing the discharge pipe in discharge position.

In the machine illustrated there is provided a base member 1 which may be chambered at 2, the intermediate portion of said member having a helical passage 3, and there being a discharge opening 4 at the lower end of the passage.

Mounted on the base member 1 is a standard comprising legs 5 fastened by cap screws 6 or equivalents to the top of the base member. The upper ends of the legs 5 are joined together to form a boss 7 and passing through said boss is a tubular vertical intake member 8. The tubular intake member 8 is in the form of a stationary hollow stud shaft provided with an enlarged

bearing portion 9 to journal thereon a rotative sleeve 10. Any suitable packing is provided adjacent the stationary bearing portion 9 and the sleeve 10 to prevent or minimize leakage of material between said members. In this instance the packing is formed of one or more cups 11 of leather or other suitable material alternatively arranged with spacing collars 12, said cups and collars being retained in position by a shoulder 13 terminating the upper end of the bearing portion 9 and by a plug 14 fastened by a key 15 or equivalent to the tubular member 8.

The sleeve 10 is fastened by cap screws 16 or equivalent to a hollow cone-shaped member 17 which in turn is fastened by cap screws 18 or equivalent to the upper end of a shell 19 which is provided with an annular passage extending in an outer portion 20 from near the upper end of the shell to near the lower end thereof, thence downwardly and inwardly in an inclined portion 21, thence upwardly and inwardly in a curved portion 22, thence upwardly in an intermediate portion 23. The upper end of the passage portion 20 terminates in a shoulder 24 and the upper end of the inclined portion 21 terminates in an annular shoulder 25 and when the machine is in operation the mercury, not shown, occupies that portion 20 of the passage extending between the shoulders 24 and 25. The portion 20 of the passage is formed between the outer wall 26 of the shell and an intermediate wall 27 of said shell, and the passage portions 22, 23 are formed between an intermediate wall 28 and an intermediate wall 29. The intermediate walls 28 and 29 need not be, and preferably are not, as long as the intermediate wall 27. The intermediate wall 27 extends upwardly and inwardly in a curved portion 30 which is spaced from the conical member 17 to form an upward extension of the passage portion 20. The curved portion 30 joins a cover portion 31 which is fastened by cap screws 32 or equivalents to a collar 33 which is mounted on the upper portion of and rotates with a vertical central shaft 34.

Extending downward from the collar 33 is a tubular member 35 forming an inner wall of the shell 19 provided with an annular lip 36 which meets the upper portion of the intermediate wall 28 to form the joint 110

37. The lower portion of the tubular member 35 forms the inner wall of a passage portion 38; the outer wall of said passage portion being formed by the inner wall 29. 5 From the foregoing it is clear that there is an annular passage leading downwardly from the intake member 8 to near the bottom of the shell 19, thence upwardly and inwardly and thence downwardly. It is 10 also clear that the walls 27, 28 overlap the wall 29 and are inserted between the walls 26, 29. The passage portion 38 terminates at its lower end in downwardly and outwardly peripherally-discharging nozzles 39 15 which are gradually reduced outwardly and which are arranged to discharge in a direction opposite to the direction of rotation indicated by the arrow *b*, Fig. 3, so that centrifugal action will to a greater or less 20 degree tend to cause flow of the ore through the machine. Under some conditions it may be advisable to extend the nozzles 39 to increase the centrifugal discharging action and for that purpose nozzle extensions 40 may 25 be provided as shown in the drawings, said nozzle extensions being fastened by cap screws 41 or equivalent to the outer wall of the shell 19 so that the bores of the nozzles and nozzle extensions aline with one another. It is understood that this machine 30 will function without the nozzle extensions 40 if so desired.

The passage portion 20 is of slightly less diameter at its lower end than at its upper 35 end and the passage portion 23 is of slightly less diameter at its upper end than at its lower end. Likewise the passage portion 38 is of less diameter at its upper end than at its lower end. This is for maximizing 40 conservation of the mercury and facilitating the flow of the metalliferous ore through the passage.

The lower end of the shaft 34 is supported in a step-bearing 41 which is fastened by 45 cap screws 42 or equivalent to the base member 1. The shaft 34 is provided with a pulley 43 just above the step-bearing 41, and the upper portion of the shaft is journaled just beneath the collar 33 at 44 in a tubular 50 upwardly extending portion 45 of the base, there being a clearance between said tubular member and the tubular member 35.

At the lowest point in the passage portion 22 is an inwardly reduced clean-out port or 55 ports 46 in which fits a tapered plug or plugs 47 having a head or heads 48 suitable for turning by a wrench, not shown. The plug is provided with an inwardly extending internally threaded sleeve 49 adapted to engage 60 the externally screw-threaded reduced portion 50 of a nipple which also comprises an enlarged externally screw-threaded portion 51. The bore of the nipple forms the outer portion of the port 46.

65 In the practice of the method with the ma-

chine above described, the desired amount of mercury will be run into the passage portion 20 of the machine and power will be applied to the pulley 43 to rotate the collar 33 and the parts connected with said collar, thus 70 causing the mercury, not shown, to form an annular body in the passage portion 20 between the shoulders 24, 25. The crushed metalliferous ore to be amalgamated will be introduced under suitable pressure through 75 the intake member 8 into the passage portion 20 and centrifugal action will cause the heavier particles, which of course are the metal particles in the ore, to occupy the peripheral portion of the tubular column of 80 downwardly moving ore. These metal particles will be forced against the inner face of the mercury body and into said body in a manner well understood in the art pertaining to centrifugal amalgamation and 85 amalgamation of the metal particles will take place, and the remaining material or tailings will flow through the passage portions 22, 23 and 38 to the nozzles 39 and will be forced outwardly from said nozzles into 90 the helical passage 3 of the base 1. The force of discharge of the material from the nozzles 39 is sufficient to cause the material to flow from the helical passage 3 through 95 the discharge opening 4.

When it becomes necessary or desirable to remove the amalgam from the machine, operation of the machine will be stopped, whereupon the amalgam will flow into the lower portions of the passage portions 20 and 22. Pipes indicated in broken lines at *a* 100 Fig. 1, will be screw-threaded onto the enlarged portion of the nipples 51, and a suitable wrench, not shown, will be inserted in the pipes to engage the heads 48 of the plugs. Turning of the wrench will unscrew the 105 plugs and the amalgam will flow through the ports 46 into the pipes *a* and thence into a suitable container, not shown, placed at the discharge ends of said pipes *a*. 110

It is noted that the centrifugal action aiding in the discharge of the tailings from the shell is of advantage for the reason that the lower end of the passage in the shell is thereby cleared of the tailings so that the 115 pressure of the incoming ore will not cause the particles of the ore to become too closely packed in the passage. It is readily seen that owing to the centrifugal action tending to keep clear the lower end of the passage 120 the pressure required to force the ore through the machine is less on a given character of ore than if the centrifugal discharging action were not provided for. By having less pressures, it is clear that leakage of 125 the material past the packing cups 11 and through the various joints of the shell is minimized and is, in fact, practically eliminated.

From the foregoing it is clear that the 130

centrifugal action of the tailings in the discharge end of the shell passage is sufficient to prevent clogging of the passage even though the force of the ore feed at the feed 5 end of the passage be insufficient of itself to cause the ore to flow through the machine at a desirable rate of speed. The advantage of this is that pressures inside of the shell may be minimized so as to minimize leakage 10 past the packing 11 and through the joint of the various sections of the shell, thus the centrifugal action of the hollow rotating column of ore is utilized to aid in moving the column of ore through and in contact 15 with a hollow body of mercury.

I claim:

1. The method of obtaining metal from ore, which consists in causing the centrifugal action of a hollow rotating column of 20 ore to move said column through and in contact with a hollow body of mercury, and discharging the tailings in a direction opposite to the direction of rotation so as to prevent too close packing of the particles of 25 ore in the column.

2. The method of obtaining metal from ore, which consists in causing the centrifugal action of a hollow rotating column of ore to aid in moving the column of ore through 30 and in contact with a hollow body of mercury, and discharging the tailings in a direction opposite to the direction of rotation so as to prevent too close packing of the particles of ore in the column.

3. The method of obtaining metal from ore, which consists in applying pressure behind a hollow rotating column of ore to move said column through and in contact 40 with a hollow body of mercury, utilizing the centrifugal action of said rotating column to aid in moving the column of ore through said body of mercury, and discharging the tailings in a direction opposite to the direction of rotation so as to prevent too close 45 packing of the particles of ore in the column.

4. The method of obtaining metal from ore, which consists in causing the discharge of tailings from a hollow rotating column of ore in a direction opposite to that of rotation to prevent too close packing of the 50 particles of ore in the column, and effecting amalgamation of the metal at the periphery of the column.

5. The method of obtaining metal from ore, which consists in applying pressure behind a hollow rotating column of ore to aid in moving said column through and in contact with a hollow amalgamating body, thence downwardly, and discharging the 60 tailings in a direction opposite to the direction of rotation so as to prevent too close packing of the particles of ore in the column.

6. The method of obtaining metal from ore, which consists in applying pressure behind a hollow rotating column of ore to aid 65

in moving said column through and in contact with a hollow amalgamating body, thence inwardly, and discharging the tailings in a direction opposite to the direction of rotation so as to prevent too close packing 70 of the particles of ore in the column.

7. The method of obtaining metal from ore, which consists in applying pressure behind a hollow rotating column of ore to aid in moving said column through and in contact 75 with a hollow amalgamating body, thence downwardly, utilizing the centrifugal action of said rotating column to aid in moving the column of ore through said amalgamating body, and discharging the tailings in a direction opposite to the direction of rotation 80 so as to prevent too close packing of the particles of ore in the column.

8. The method of obtaining metal from ore, which consists in applying pressure behind a hollow rotating column of ore to aid in moving said column through and in contact with a hollow amalgamating body, thence inwardly, utilizing the centrifugal action of said rotating column to aid in moving 85 the column of ore through said amalgamating body, and discharging the tailings in a direction opposite to the direction of rotation so as to prevent too close packing of the particles of ore in the column.

9. The method of obtaining metal from ore, which consists in applying pressure behind a hollow rotating column of ore to aid in moving said column through and in contact with a hollow amalgamating body, thence downwardly, thence inwardly, and discharging the tailings in a direction opposite to the direction of rotation so as to prevent too close packing of the particles of ore 95 in the column.

10. The method of obtaining metal from ore, which consists in applying pressure behind a hollow rotating column of ore to aid in moving said column through and in contact with a hollow amalgamating body, thence downwardly, thence upwardly, and discharging the tailings in a direction opposite to the direction of rotation so as to prevent too close packing of the particles of ore 110 in the column.

11. The method of obtaining metal from ore, which consists in applying pressure behind a hollow rotating column of ore to aid in moving said column through and in contact with a hollow amalgamating body, thence downwardly, thence inwardly and upwardly, and discharging the tailings in a direction opposite to the direction of rotation so as to prevent too close packing of the particles of ore 120 in the column.

12. The method of obtaining metal from ore, which consists in applying pressure behind a hollow rotating column of ore to aid in moving said column through and in contact with a hollow amalgamating body, 130

thence inwardly, thence upwardly, and discharging the tailings in a direction opposite to the direction of rotation so as to prevent too close packing of the particles of ore in 5 the column.

13. The method of obtaining metal from ore, which consists in applying pressure behind a hollow rotating column of ore to aid in moving said column through and in contact with a hollow amalgamating body, thence inwardly, thence inwardly and upwardly, and discharging the tailings in a direction opposite to the direction of rotation so as to prevent too close packing of the particles of ore in the column.

14. The method of obtaining metal from ore, which consists in applying pressure behind a hollow rotating column of ore to aid in moving said column through and in contact with a hollow amalgamating body, thence downwardly, thence inwardly, utilizing the centrifugal action of said rotating column to aid in moving the column of ore through said amalgamating body, and discharging the tailings in a direction opposite to the direction of rotation so as to prevent too close packing of the particles of ore in the column.

15. The method of obtaining metal from ore, which consists in applying pressure behind a hollow rotating column of ore to aid in moving said column through and in contact with a hollow amalgamating body, thence downwardly, thence upwardly, utilizing the centrifugal action of said rotating column to aid in moving the column of ore

through said amalgamating body, and discharging the tailings in a direction opposite to the direction of rotation so as to prevent too close packing of the particles of ore in 40 the column.

16. The method of obtaining metal from ore, which consists in applying pressure behind a hollow rotating column of ore to aid in moving said column through and in contact with a hollow amalgamating body, thence downwardly, thence inwardly and upwardly, utilizing the centrifugal action of said rotating column to aid in moving the column of ore through said amalgamating 45 body, and discharging the tailings in a direction opposite to the direction of rotation so as to prevent too close packing of the particles of ore in the column.

17. The method of obtaining metal from ore, which consists in applying pressure behind a hollow rotating column of ore to aid in moving said column through and in contact with a hollow amalgamating body, thence inwardly, thence upwardly, utilizing the 50 centrifugal action of said rotating column to aid in moving the column of ore through said amalgamating body, and discharging the tailings in a direction opposite to the direction of rotation so as to prevent too close packing of the particles of ore in the column.

Signed at Los Angeles, California, this 9th day of January, 1918.

SAMUEL G. MUSSER.
